UNITED STATES PATENT OFFICE.

GEORGE H. GASKINS, OF PORTSMOUTH, VIRGINIA.

MACHINE FOR POLISHING RINGS.

SPECIFICATION forming part of Letters Patent No. 699,514, dated May 6, 1902.

Application filed January 10, 1902. Serial No. 89,189. (No model.)

To all whom it may concern:

Be it known that I, GEORGE H. GASKINS, a citizen of the United States, residing at Portsmouth, in the county of Norfolk and State 5 of Virginia, have made certain new and useful Improvements in Machines for Polishing Rings, of which the following is a specification.

My invention is an improvement in machines for polishing rings; and the invention consists in certain novel constructions and combinations of parts, as will be hereinafter described and claimed.

In the drawings, Figure 1 is a top plan view, 15 and Fig. 2 a side elevation, partly in section, of a machine embodying my invention. Fig. 3 is a cross-sectional view on about line 3 3 of Fig. 1. Fig. 4 is a detail elevation of the rear side of the upper portion of the ring table or carrier on the line indicated by the arrow in Fig. 3. Fig. 5 is a detail perspective view of one of the heads of the strap-carrier. Fig. 6 is a detail perspective view of the detent-pawl shown in Figs. 3 and 4. Fig. 7 is 25 an elevation of the ring-table, showing a different style of detent-pawl; and Fig. 8 is a detail perspective view of the detent-pawl shown in Fig 7.

In carrying out my invention I provide a 30 ring-carrier for the rings to be polished, a polishing-strap A to operate between its ends on said ring, and a carrier for said strap, which is capable of reciprocation, as more fully described hereinafter. In the construction shown I employ a suitable framing, which includes a base B, having bearings for a shaft C, which may be driven in any suitable manner and is connected by means of a crank C' and a pitman C² with the reciprocating carrier for the strap A. I also support on the base B shears or guides D, upon which the strap-carrier reciprocates, and said strap-carrier is formed with the opposite heads E, which may be alike, and one of 35 which is connected with the pitman C² by means of a bolt C³, passed through the opening e in the head E and secured by a nut or in other suitable manner, as may be desired.

The heads E are adapted at E' to engage 40 and slide along the guide-rails D and may be preferably made cruciform, as shown, with one of the lateral arms E² somewhat shorter

than the arm E³ and the latter provided with an opening at e³ for one of the shanks of the intermediate brace for the opposite heads E. 55 The shorter arm E² is arranged at the rear for the purpose of bringing the points of connection of the polishing-strap nearer the rear side of the machine, and consequently nearer the ring-carrier, as will be understood from Fig. 1 of the drawings. The upper and lower arms E⁴ and E⁵ are provided with openings e⁴ and e⁵ for the shanks of the intermediate brace, and the upper arm E⁴ is also provided near its upper end with a non-circular opening E⁶ for the strap-carrying bar F, one of which is mounted in each of the heads E. 65

A brace extends between the opposite heads E and connects the same in such manner as to square the heads, so they will slide properly 7c along the guide-rails and will not jam thereon as the strap-carrier is reciprocated. This intermediate brace G is provided at its ends with three shanks g³, g⁴, and g⁵, which extend, respectively, through the openings e³, e⁴, and e⁵ and receive the nuts g and g' on the inner and outer sides of the heads E, so the said nuts may be tightened to adjust the heads in such manner as to cause the same to stand truly parallel and operate squarely upon their 80 sides. This adjustment may be effected by loosening the nuts on one side of the heads and tightening them on the opposite side, as may be required.

As shown, the intermediate brace G is composed of the sections G' and G², the latter carrying the shanks g³ at its opposite ends and the section G' carrying the shanks g⁴ and g⁵ at its opposite ends, and both sections G' and G² being secured together by bolts or 90 rivets, as shown at G³ in Fig. 1. By the described construction I am able to adjust the opposite heads E of the carrier and to brace them apart, so they will operate squarely upon their guide-rails. 95

The polishing-strap A may be of cloth supplied with the polishing medium, which may be emery or other suitable material, held to the cloth by glue or in other suitable manner, or such polishing-strap may be of crocus cloth for very fine work, and the opposite ends of the strap A are secured at a upon pins or other suitable devices on the bolts F, the said bolts being squared to fit in the openings E^c 100

of the heads E, so they will be held from turning, and the shanks f of said bolts being threaded to receive the nuts f', which secure the bolts and which bear against the springs 5 F', whose upper ends are deflected to actuate the bolts F, as shown in Fig. 2, and whose lower ends are secured by the nuts g', which bind them to and against the outer sides of the heads E.

10 The polishing-strap A is looped or coiled at A' around the ring or other object to be polished, and as the strap is moved longitudinally by the reciprocation of its carrier it will be caused to polish the ring and also to 15 feed the ring, as will be described.

The ring H to be polished is held on a suitable carrier having a table I, forming a support for the ring, and the base of which is movable along ways J, which extend transversely in the direction of reciprocation of the strap-carrier, a screw J' being arranged for operation to adjust the ring-carrier toward and from the strap to adjust or adapt the device for polishing rings of different sizes. In operation the ring is placed on the table I and a keeper K in the form of a bar is secured between its ends by a nut K', so its ends will overlap the ring and retain it upon the table. A pawl or detent is arranged to permit the 30 movement of the ring rotarily in one direction, but to lock it from movement in the opposite direction. This pawl may be a plate L, as shown in Figs. 3, 4, and 6, pivoted at one end at L' upon a bolt M and secured by a nut M' and 35 arranged at its free end at l for the passage of the ring and to permit the movement of the ring freely in the direction indicated by the arrow in Figs. 1 and 4 and to lock the ring against movement in the opposite direction. 40 By this means as the strap A is moved in one direction it will cause a partial rotation of the ring H in the direction indicated by the arrow, Fig. 1, while the reverse movement of the strap will polish the ring, the latter being held from rotation at such time by the pawl, 45 as before described. The pawl l is adapted for use upon brass or similar soft metals, while in Figs. 7 and 8 I show a pawl adapted for use on iron, steel, or like harder metals. 50 This pawl N (shown in Figs. 7 and 8) may be substituted for the pawl l, the bolt M being adapted to receive either of said pawls, as will be understood from Figs. 3, 4, and 7, the machine being thus adapted for the treatment 55 of soft-metal or hard-metal rings, as may be required.

In the operation of the invention it will be noticed that the strap A is so held that all slack is taken up by the action of the springs 60 F', which exert a tension upon the devices which secure the opposite ends of the strap A, thus avoiding any injury to the strap which might result from its being slack, and also enabling me to adjust the tension of the 65 strap as well as adjust the length of same to operate upon different sizes of rings, the adjustment of the length of the strap co-operat-

ing with the adjustment of the ring-carrier in a direction transverse to the path of the strap in securing an accurate adjustment of 70 the strap to operate upon different sizes of rings, as may be desired.

While the invention is especially designed for polishing metal and metal in the form of rings, it will be understood it may be employed for polishing other materials and other forms, it only being necessary to furnish or adapt the work-holder I with or for means for receiving and holding the particular work to be operated upon.

I provide both heads E with openings e for the bolt C³, which secure the pitman C², so the pitman may be connected with either end of the carrier, as convenience may require.

Having thus described my invention, what I claim, and desire to secure by Letters Patent, is—

1. An apparatus substantially as described comprising a carrier for the polishing-strap provided with opposite heads having the plurality of openings for the shanks of the intermediate brace, the intermediate brace having at its ends threaded shanks passing through the openings in the opposite heads, the nuts on said shanks on opposite sides of 95 the heads, the springs on the outer sides of the heads and held by the nuts thereof and deflected to operate upon the strap-holding bolts, the strap-holding bolts and their nuts, the guideways upon which the strap-carrying 100 heads reciprocate, means for reciprocating the carrier and means for holding the work to be operated upon substantially as set forth.

2. The combination in a machine substantially as described of a reciprocating strap-carrier, guideways for said carrier, and a ring-holder provided with means for securing the ring in a plane approximately parallel with the direction of movement of the strap-carrier whereby the ring will be secured with its 110 axis at a right angle to the line of movement of the strap-carrier substantially as set forth.

3. The combination of the reciprocating carrier for the polishing-strap having opposite heads, devices for securing the opposite 115 ends of the strap, said devices being movable in the opposite heads of the carrier, and springs by which to give tension to said strap-securing devices substantially as set forth.

4. The combination in an apparatus substantially as described with the opposite carrier-heads of an intermediate brace extending between said heads and provided at its ends with the three threaded shanks extending through the heads, and nuts on said shanks 125 on opposite sides of the heads, substantially as set forth.

5. In an apparatus substantially as described the combination with the strap-carrier heads of the bolts movable in said heads 130 and provided with means for securing the ends of the polishing-strap, and the springs acting upon said bolts whereby to give tension to the same substantially as set forth.

6. A machine substantially as described comprising the reciprocating carrier provided with means for securing the opposite ends of a polishing-strap and means for supporting said carrier of a ring-holder having a support and securing means for the ring, and a detent for said ring adapted to permit the same to turn in one direction and to lock it from turning in the opposite direction substantially as set forth.

7. The combination in a machine substantially as described with means for supporting the ring to be polished, of detent mechanism by which to lock said ring from turning in one direction and to permit it to turn in the opposite direction substantially as set forth.

8. In a machine substantially as described the combination of a table for supporting the ring, a keeper arranged at its ends to overlap the ring and hold it upon the table, and means for securing the keeper substantially as set forth.

9. The combination of the ring-holder,

means for securing the ring, and a detent-pawl arranged to operate on the ring and to prevent the same from turning in one direction, substantially as set forth.

10. In a machine substantially as described the combination of the reciprocating carrier for the polishing-strap, a holder for the work to be polished and guides for said holder extending in a direction transverse to the path of the strap-carrier and means for adjusting the work-holder substantially as set forth.

11. The combination in a machine substantially as described of the reciprocating carrier, a polishing-strap connected at its ends with the said carrier and adapted between its ends to be looped around the work to be polished, and a holder for such work substantially as set forth.
